AMMUNITION PRIMING COMPOSITION

Philip H. Burdett, Bridgeport, and Gordon M. Calhoun, Fairfield, Conn., assignors to Remington Arms Company, Inc., a corporation of Delaware

No Drawing. Application May 24, 1941,
Serial No. 394,994

4 Claims. (Cl. 52—4)

This invention relates to priming mixtures for ammunition and comprises the discovery that several salts of triazoacetic acid possess properties which render them particularly valuable as ingredients of such mixtures.

Conventional priming mixtures comprise three classes of ingredients:

First, a fuel or substance to be burned with the production of a flame of sufficient heat and intensity to effectively ignite propellant powder.

Second, an oxidizer comprising a chemical compound susceptible to being broken down and freeing oxygen for the combustion of the fuel. Third, a percussion sensitive ingredient which, under the blow of the firing pin of a firearm, breaks down with the creation of heat and pressure adequate to initiate and sustain the reaction between oxidizer and fuel.

The percussion-sensitive ingredient is frequently referred to as an "explosive," because it is capable of being disrupted by a blow. There are, however, certain explosives, of which lead styphnate is typical, which are not of themselves dependably susceptible to explosion by a firing pin blow, but after ignition perform the function of a combustion initiator in an eminently satisfactory manner. With such an explosive it is desirable to use another ingredient ordinarily referred to as a "sensitizer." Such sensitizers may not of themselves be more sensitive to percussion than the explosive they sensitize, but in admixture with an explosive, such as lead styphnate, form a composition which is not only quite highly sensitive to percussion but under percussion explodes without undue violence and with the creation of the heat and pressure ample to produce the oxidizer-fuel reaction.

It has been found that several salts of triazoacetic acid, particularly the lead salt, are very valuable sensitizers for ammunition priming mixtures of the lead styphnate type. A typical mixture consists of:

	Per cent
Lead styphnate	32
Lead nitrate	30
Lead sulfocyanate	8
Lead triazoacetate	10
Glass	20

Other triazoacetates, such as those of silver or potassium, may replace the lead salt with desirable results.

Other combustion initiators, oxidizers (particularly the non-corrosive type) and fuels may be used and the proportions of the ingredients varied widely. A practical range of proportions of the salt of triazoacetic acid is from about 1%

to 15% of the priming mixture. The normal lead triazoacetate, which probably has the formula:

may be prepared by the double decomposition method from the potassium salt of triazoacetic acid and lead nitrate. It forms large white glistening needles somewhat soluble in cold water.

10 The normal silver salt may be prepared in a similar manner. It forms pure white crystals.

In the preparation of the potassium salt, ethyl chloroacetate is refluxed with sodium azide in alcohol diluted with enough water to keep the sodium azide in solution. After several hours a comparatively large volume of water is added, and the oily layer separated by means of a separatory funnel. This non-aqueous layer is treated directly (or after distillation) with aqueous potassium hydroxide. The potassium salt precipitates as creamy white plates, upon evaporation of the resulting solution.

15 20 25 The uranyl salt, probably having the formula:

30 35 40 is obtained as a bright yellow powder upon evaporation and cooling of the solution obtained by adding 1 part of triazoacetic acid ($\text{N}_3\text{CH}_2\text{COOH}$) in 8 parts of water to 2.51 parts of uranyl nitrate in 10 parts of water.

As many apparently widely different embodiments of this invention may be made without departing from the spirit and scope thereof, it is to be understood that this invention is not limited to the specific embodiments thereof except as defined in the appended claims.

We claim:

1. An ignition mixture containing approximately:

	Per cent
Normal lead triazoacetate	10
Lead styphnate	32
Lead sulfocyanate	8
Lead nitrate	30
Glass	20

2. An ignition mixture containing approximately:

	Per cent
Salt of triazoacetic acid	10
Lead styphnate	32
Lead sulfocyanate	8
Lead nitrate	30
Glass	20

55 60 65 70 75 80 the salt of triazoacetic acid being that of a metal

from the group consisting of potassium, silver and lead.

3. An ammunition priming mixture comprising an oxidizer, a fuel, a combustion initiator, and a salt of triazoacetic acid as a sensitizer, said salt being that of a metal from the group consisting of potassium, silver, lead and uranyl.

4. A priming mixture for ammunition containing lead styphnate and a salt of triazoacetic acid, said salt being that of a metal from the group consisting of potassium, silver, lead and uranyl.

PHILIP H. BURDETT,
GORDON M. CALHOUN.
